JOHN R. PADESKY, OF LA CROSSE, WISCONSIN, ASSIGNOR, BY MESNE ASSIGNMENTS,
TO MOTO METER GAUGE & EQUIPMENT CORPORATION, OF LONG ISLAND CITY, NEW
YORK, A CORPORATION OF DELAWARE

INSTRUMENT PANEL BOARD

Application filed July 28, 1928. Serial No. 295,947.

This invention relates to instrument panel boards and particularly those used upon motor cars.

In such panels it has been desirable to arrange the instruments so that the diffused light from electric lights will be deflected upon the dials of the instruments. In order to do this it has been customary to secure shields to the panel board partially surrounding the openings in the panel where the electric light is positioned and these shields extend around the bulb of the light in a way to prevent the direct rays falling upon the instrument dials. In some cases the shields extend as much as $\frac{2}{3}$ of the circumferential distance around the light opening and this has required considerable care to make and secure the separate parts, so that they will fit accurately together.

This improvement has resulted in a saving of labor and material and insures a more accurate and uniform positioning of the shield upon the panel. It has also been found desirable to form additional shields about some of the instrument openings, thereby further improving the character of the lighting of the panels. In some cases the shields about the light openings can be dispensed with and the shields about the instrument openings be depended upon to diffuse the light.

In some instances, as explained, the shield extends over more than two thirds of the circumference of the opening and in some instances the shield is preferably non-continuous, consisting of a plurality of parts spaced slightly apart, and in all instances it is a decided advantage to dispense with the necessary fitting of the parts and form them in a way to insure their being accurately and firmly secured with a minimum amount of labor and material.

In a general way these objects are accomplished by first forming the panel plate with irregular shaped openings and thereafter bending the offset portion to form the shield and thereby at the same time producing a substantially perfect circular opening.

Other objects and advantages will be in part indicated in the following description

and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

In the drawings Figure 1 is a front view of the panel with partially formed light openings on the left half and completely formed light openings on the right half. Fig. 2 is a perspective view showing the offset or irregular portion turned up to form the shield. Fig. 3 is a front view of part of a panel showing non-continuous shields and Fig. 4 is a front view of a modified structure having its offset portion turned up to form a shield, while Fig. 5 is a left end view of Fig. 4.

Referring to the drawings 1 indicates an instrument panel; the instrument openings are indicated by 2 and the electric light openings are marked 3.

As heretofore explained, some of these openings are formed irregular in shape due to offset portions, and these offset portions are to be turned up to form shields partially extending around a circular or otherwise regularly shaped opening.

In Fig. 1 there are shown offset portions 4 both for the light openings and for the instrument openings. In the case of the light openings 3 the shield is intended to extend around substantially two thirds of the circular opening. Consequently the offset portion is formed with that end in view, and when this offset portion is turned up at right angles to the panel the upturned part forms the shield while the bent edge at the intersection of the panel and the offset portion, together with the curved portion intermediate the offset ends, will form the desired circular opening. As compared with old methods of forming the shields of the proper shape and then fitting them to the openings and thereafter securing them to the panel, it is apparent that this improvement repre-

sents a considerable saving in labor and material. Moreover, this improved method is much more expeditious and satisfactory than the old method because it avoids the accuracy and care required in the old method to secure a perfect fit and a secure fastening.

In the modified structure Fig. 4 there is shown a light opening of rectangular shape with offset portions 5 of such character and dimensions that when these offset portions are turned up a regular rectangular shaped opening is thereby formed with integral shields suitable to co-operate with the rest of the panel to cause the proper lighting effect upon the dials of the instrument, it being understood that this improvement is especially designed for use with instrument boards having the concealed lighting effect. It is also possible to form the shields in sections as shown in Fig. 3.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of United States:—

1. The method of manufacturing an instrument panel board which consists in cutting out of sheet metal a suitable blank; forming an aperture in said blank through which an instrument therebehind may be observed, said aperture being initially formed with an irregular contour and affording a projecting portion in the plane of said blank and extending inwardly from the periphery of said aperture; and then deflecting said projecting portion out of the plane of said blank and bending and stretching said portion to cause it to conform to the general shape of said aperture and to constitute a substantially perpendicular flange about a portion of said aperture.

2. The method of manufacturing an instrument panel board which comprises cutting out of sheet metal a suitable blank; forming an aperture in said blank, said aperture being initially formed of an irregular shape and comprising a plurality of arcuate walls connected together by substantially radial walls, the portion of said blank connecting said substantially radial walls comprising an inwardly projecting sector arranged in the plane of said blank; deflecting said sector out of the plane of said blank

along a line comprising a continuation of one of said arcuate walls to give to said aperture a regular shape; and bending and stretching said sector to cause it to lie in a plane substantially perpendicular to said blank to constitute a flange about said aperture.

3. The method of manufacturing an instrument panel board having an integrally formed light deflector, which comprises cutting out of sheet metal a suitable blank; forming therein two apertures one adapted to receive a light bulb and the other adapted to permit observation of an instrument placed therebehind, one of said apertures being of irregular form and bounded by a plurality of arcuate walls of unequal radii and substantially radial walls connecting said arcuate walls, the portion of the blank connecting said radial walls comprising an inwardly projecting sector; deflecting said sector out of the plane of said blank on an arcuate line constituting a continuation of the larger arcuate wall of said aperture; and bending and stretching said sector to cause it to project laterally from said blank to form a light deflecting flange about a portion of said aperture.

In witness whereof, I have hereunto subscribed my name.

JOHN R. PADESKY.
